UNITED STATES PATENT OFFICE.

AMOS A. TOTMAN, OF FITCHBURG, MASSACHUSETTS, ASSIGNOR, BY MESNE ASSIGNMENTS, TO QUABAUG RUBBER COMPANY, OF NORTH BROOKFIELD, MASSACHUSETTS, A CORPORATION OF MASSACHUSETTS.

MACHINE FOR PACKAGING RINGS.

1,217,532.

Specification of Letters Patent. Patented Feb. 27, 1917.

Application filed November 21, 1913. Serial No. 802,302.

To all whom it may concern:

Be it known that I, AMOS A. TOTMAN, of Fitchburg, in the county of Worcester and State of Massachusetts, a citizen of the United States, have invented a new and useful Improvement in Machines for Packaging Rings, of which the following is a specification.

The purpose of my invention is the selecting of a predetermined number of articles and the packing of them in a carton. For this purpose I have shown a machine embodying my invention in a form useful for packing rubber jar rings such as are used for closing glass fruit jars and the like. Such rings are usually made of uniform thickness and in the form of my invention shown, mechanism is provided to take from a magazine a number of rings aggregating a given thickness, carry them to a carton, place them therein and close the carton, tucking in the flaps so that the carton is ready for shipping. The rings being of equal thickness, an equal number of rings will be packed in each carton.

My invention will be understood by reference to the drawings in which it is shown in its preferred form.

Figure 1 is a plan of the machine.

Figs. 2, 3 and 4 are sections taken on line 2—2, 3—3 and 4—4 of Fig. 1, looking in the direction of the arrows.

Fig. 5 is a side elevation looking from the left hand side of Fig. 1.

Fig. 6 is a fragmentary side elevation looking from the right hand side of Fig. 1.

Fig. 7 is a detail of the box clamping mechanism, and

Fig. 8 is a perspective view of a carton for which this machine is particularly fitted.

A is the table from which the various parts are supported. Upon pedestals A¹ at one end of the table are mounted bearings A² for the cam shaft B which carries at one end a pulley B¹ connected to the source of power. Upon the shaft B are mounted the cams by which motion is given to the various parts.

Generally speaking, the machine comprises a ring feed, a ring selecting and carrying mechanism, a ring grasping and depositing mechanism, a box feed and a box

closer. The ring feed comprises an endless belt conveyer C which forms a portion of the floor of a horizontal magazine C¹. The sides of this magazine are formed by rails c supported from the floor of the magazine on legs c¹. The conveyer passes over one pulley C² and also over a second pulley (not shown) fastened to the axis of the ratchet C³ to be rotated therewith. The ratchet is moved intermittently in the following manner: On the cam shaft B is mounted a disk C⁴ carrying a crank pin c⁵ on which one end of the pitman C⁵ is mounted, the other end thereof being pivotally connected to a radius arm C⁶ mounted to turn on the axis of the ratchet C³.

This radius arm C⁶ carries a pawl C⁷ which engages the teeth of the ratchet, and with each rotation of the cam shaft moves the ratchet in the machine shown the distance of six teeth. As shown, the shape of the pawl is such as to insure its engagement with the ratchet teeth, but a spring connected in the usual way will insure its engagement.

On the magazine C¹ is also mounted a hold-down C⁸. As shown, this comprises an arch the radius of which is approximately equal to the radius of the rings to be boxed and is so located that the rings will pass under it and be held by it from rising off of the conveyer. As shown, it is made in three parts, two uprights attached to the floor of the magazine and the arch proper which is so attached to the uprights as to be adjustable to accommodate rings of slightly varying diameters. C⁹ is a stop mounted on a slide c¹⁰ running in ways c¹¹ on the magazine floor. An adjusting screw c¹² running through threaded ears, one on the magazine floor and the other on the slide, adjusts the stop and holds it in place when adjusted. This stop is forked at its upper end to form a passage through which the ring lifter may pass to lift out the predetermined number of rings as below described.

The rings are taken from the magazine by a carrier comprising two members, a ring lifter and ring holder, the former passing into the opening in the rings and lifting the predetermined number from the other rings.

in the magazine and the latter holding or clamping the rings so lifted upon the lifter. The number of rings lifted depends upon the adjustment of the stop C^9 with reference 5 to the opposing face of the hold-down C^8 , and this adjustment may be easily made when the rings are all of a given thickness. C^{10} is a weight or back stop which rests on the conveyer and travels with it holding the 10 rings in place against the stop C^9 .

The ring lifter comprises an arm D mounted to slide in the rotary head E . Its rear end is adapted to engage one arm of a bell crank cam lever D^1 pivoted to the frame 15 piece A^3 , the other arm of this lever carrying a cam roll d^1 which rides on a cam D^2 on the shaft B . A spring d^2 holds the arm D in its rearward position, one end of this spring being attached to the arm D and the 20 other end to a bracket E^1 extending from the head E and grooved to serve as a runway for the arm D . The arm D carries a gage d^3 against which the rings when lifted rest and which is adjustable, the distance 25 from its front face to the end of the arm being equal to the thickness of the number of rings to be lifted and packed. The cam D^2 is so shaped as at the proper time to drive the arm D forward between the forks 30 of the stop C^9 so that it will enter the opening in the rings which are against the stop and its forward end will be in approximately the plane of the opposing edge of the hold-down C^8 .

The ring holder F is mounted to slide in a hinged block E^2 on top of the head E so that it may rock in a vertical plane as well as move horizontally with the head. A support projects forward from the block, comprising an arm f carrying a grooved guide f^1 at its end having a strap f^2 bolted across the groove to keep the holder F in place. A similar strap f^3 keeps the rear portion of the holder in a suitable groove in the block 45 E^2 . This holder is held normally in rearward position by a spring f^4 attached at one end to the holder F and at the other end to an eye on top of the strap f^3 . A stop f^5 adapted to engage the block E^2 limits the 50 rearward motion of the holder F . The holder F is moved forward by the bell crank lever F^1 pivoted to A^3 , one end of this lever being adapted to engage the rear end of the holder F and the other end of said lever 55 engaging the cam surface F^2 .

The stop f^5 should be adjusted so that the holder when in rearward position shall hold the rings against the gage d^3 on the arm D . As shown in Fig. 5 the holder F is in forward position. After the arm D has been moved forward into the opening in the rings and has begun to lift them the cam F^2 releases the holder F so that it is drawn rearward by the spring f^4 and drops off the hold-

down C^8 onto the rings holding them against the gage during the turning of the head. During this time the head is in lifted position and so remains until it returns into position to bring the arm D and holder F in line with the ring magazine when it drops 70 allowing the arm D to fall between the forks in the stop C and the holder F to fall on the hold-down C^8 as shown in Fig. 5.

The carrier comprising two members as above described and mounted in the head E , 75 carries the rings from their position in the magazine to a position over the box in which the rings are to be packed. For this purpose the head E is given two movements, a vertical movement to lift the rings out from 80 behind the stop C^9 and a rotary or swinging movement to carry them over to the mechanism which deposits them in the box. The head E is mounted on a post E^3 which has a vertical movement in a sleeve E^4 mounted 85 on the frame piece A^3 . A vertical movement is given to the post E^3 by means of the cam lever E^5 on which the bottom of the post rests. The cam lever E^5 is fulcrumed on the frame piece A^3 and carries at its farther end 90 a cam roll e which engages the cam E^6 .

The rotary or swinging movement is given to the head E in the following manner: The shaft E^4 is recessed to receive a collar E^7 which is splined to the post E^3 so that 95 the post will slide in the collar and will be rotated by the rotation of the collar. This collar E^7 carries an arm E^8 which is connected by a connecting rod E^9 with a cam lever E^{10} pivoted at E^{11} to a stand e^1 on the 100 table A . The short arm e^2 of the lever E^{10} carries a cam roll e^3 which engages the cam e^4 . A spring E^{12} connects E^{10} with a support A^4 so as to hold the cam and its roll 105 in engagement and the head normally in the position shown in Fig. 1.

These parts are so timed that the cam lever E^5 first operates to lift the head so that the rings may clear the stop C^9 as above referred to and thereafter the post will be 110 rotated carrying the head with it to bring the rings within reach of the depositing mechanism.

In order that the rings left in the magazine shall not be pressed forward until the 115 rings in front of them clear the stop C^9 and magazine, there is shown a slide G mounted to slide on the magazine floor and through an opening in the bottom of the stop C^9 . This slide G is given a forward movement 120 by means of the cam G^1 which engages an arm G^2 mounted on a shaft G^3 carried in a bearing G^4 mounted on the table A . This shaft also carries an arm G^5 connected with the slide G . A spring G^6 attached to the arm G^5 and the magazine C^1 or other stationary element holds the arm G^2 against the cam surface G^1 .

The motion of the head is sufficient to turn the rings into a position such that their diameters are parallel with the magazine C¹ where they are grasped by a pair of hands H, H¹. These hands are shown particularly in Figs. 3 and 4, H being the front hand and H¹ the rear hand. These hands are carried by arms which are mounted on a shaft H² supported in a bearing A⁵ on the table A. The shaft H² carries an arm H³ to which is attached a forked arm H⁴ carrying a cam roll h. The forked end of the arm H⁴ straddles the cam shaft B and the cam roll h rests against the cam h¹. A spring h² holds the roll h and cam h¹ in contact (see Fig. 3). In addition, however, the rear hand H¹ is given a movement toward and from the front hand so as to clamp the rings against the front hand. For this purpose the arm H⁵ upon which the front hand is mounted, is attached to a sleeve H⁶ which slides on the shaft H². This sleeve is grooved as at h³ and in the groove runs a pin h⁴ upon the end of a cam lever h⁵ carrying a roll h⁶ at its farther end, which roll engages the cam surface h⁷. The fulcrum of this lever is a stud mounted on the frame h⁸ on the table A. A spring h⁹ one end of which is connected to the bearing A⁵ and the other end to the lever h⁵ holds the cam roll h⁶ against its cam h⁷. A pin h¹⁰ attached to the front hand H passes through a hole in the rear hand H¹ so that the two hands will rock together. The rear hand H¹ may be adjusted on its arm toward or from the front hand by screws h¹¹. The cams h¹ and h⁶ are so timed that when the head E has swung around to bring the rings within reach of the hands the hands will be lifted to reach them. The rear hand will then be closed against the front hand and grab them and at that instant the arm D will be released and the spring d² will pull the arm rearward so that it will be freed from the rings.

It will be noted that the hand H is much larger than the hand H¹, the hand H being sufficient in size to engage substantially the area of the rings and the hand H¹ being sufficient in size to clamp them in place against the hand H. Thereafter the hands are given a downward movement into the box and the rear hand H¹ then releases pressure from the rings and both hands are withdrawn. A guide H⁷ mounted on standard H⁸ assists in steadying the rings as they are swinging around by the carrier.

On the side of the bracket E¹ is mounted a latch D³ pivoted at d⁴ and carrying a pin d⁵ which passes through an opening in the bracket E¹. The rear end of this latch is kept in closed position by means of a spring d⁶. This pin d⁵ extends through the bracket E¹ and into a hole in the side of the arm D

so as to hold the arm during the rotation of the head E in the extended position into which it has been moved by the cam lever D¹. A post D⁴ is mounted on the table A and carries an adjustable stop d⁸ in position to engage the latch D³ so that when the head E has been rotated and the rings have been carried into position between the hands H, H¹ the latch will release the arm D and allow the spring d² to withdraw it into its rearward position.

The cartons are fed forward through a guideway J and the forward box is pushed into place under the hands H, H¹ and there receives the rings and is thereafter closed, all by mechanism, now to be described.

The kind of carton best suited for packing rings and for which my machine is especially devised, is one of well known character, and is of such size as to hold a dozen rings, the rings being flat and usually cut from a piece of rubber tubing.

It is shown in Fig. 8 where 10 is the carton, 2, 2, being the side tabs and 3 being the flap or cover which is scored so that its free end can be tucked into the carton when it has been filled. Other forms of cartons are useful for this purpose, but my machine is especially designed and proportioned for a carton of this character.

The walls of the guideway J as shown are provided with lateral openings J¹ and through these openings are moved clamps J², each clamp being mounted upon a lever J³. These levers are fulcrumed at j in a yoke piece j² which is adjustably mounted below the table A. A movement toward each other is given to these clamps by means of the cam J⁴ which engages a roll on the end of the lever J⁵, a spring J⁶ holding the roll against the cam J⁴ and the lever being fulcrumed to a standard J⁷ on the table. The other end of this lever J⁵ is connected by a connecting rod J⁸ with a lever J⁹ fulcrumed on a hanger J¹⁰ depending from the table.

To the lever J⁹ is connected by a link J¹¹ a slide J¹² running in a guideway J¹³ supported under the table. Toggles j³ are pivotally connected with the lower ends of the levers J³ as well as to the slide J¹².

Thus the lifting of the slide J¹² will tend to straighten the toggles and throw the clamps J² toward each other. It is preferred to have a slotted connection between the levers J³ and the clamps J² to avoid the necessity for accurate adjustment of the movement of the clamps. In addition, however, these clamps are given a feeding movement so that they may feed the line of cartons at the proper time toward the forward end of the guideway J.

For this purpose the frame which comprises the yoke piece j², levers J³ and the clamps, together with the toggles j³, are rocked about the pivots j⁴ by means of the cam K against

which runs the cam roll k attached to the lever K^1 . The lever K^1 is mounted on a vertical shaft k^1 pivotally supported above and below in a standard K^2 , and its other end is 5 loosely attached to one of the levers J^3 so that as the lever K^1 is rocked the clamps which have engaged one or more cartons move them into the machine pushing the forward carton of the series into position to 10 be fed under the hands H, H^1 at the proper time. The carton may be fed to the clamps automatically or by hand as desired.

To push the forward carton into position under the hands a frame M is provided 15 which is mounted on the end of a bent rod M^1 connected by a link M^2 to a lever M^3 mounted to swing on a sleeve M^4 mounted on a post M^5 on the table A . This connecting rod M^3 is connected to a cam rod M^6 carrying a cam roll M^7 in engagement with a cam M^8 . A spring M^9 keeps the cam roll in engagement with the cam. To the rod M^1 is also attached a slide m running on rods m^1 set at any angle to the path of the carton 20 which the frame M feeds so that the frame M will move slightly away from the forward carton in the guideway J . In Fig. 1 these parts are shown with the part M in its forward position. It is moved rearward at 25 the proper moment past the front of the guideway J so that an opening will be left into which the clamps J will feed the carton. It will be understood that in this feeding operation the clamps move but a short distance, the carton or cartons which they move 30 pushing forward the cartons in front of it. A plate N mounted above the guideway J and over its front end engages the flap 3 of the carton holding it open until the carton 35 is filled. In Fig. 3 the shape of the plate is seen. It has preferably a downwardly-projecting part n which extends nearly into the carton so that it is certain to engage the flap 3 and hold it in vertical position. The 40 other end n^1 of the plate is narrower so that while it continues to hold the flap vertical, the flap can easily slip off the part n^1 when the closing mechanism engages the flap to close it in the carton as now to be described. 45 After the carton is positioned it is held in place during the filling operation by a plate L which is hinged to a standard L^1 mounted on the table and is turned downward so that a lip l projecting from its outer 50 edge reaches over and into the carton on the side opposite from that from which the flap 3 projects. Thus at this moment the carton is held open by the plate N which engages its flap 3 and the lip l which 55 engages its opposite side. This plate L is operated by means of a cam lever L^2 pivoted to a support mounted on the table A and connected to the plate L by the link l^1 . At its farther end this lever L^2 is pro-

vided with a cam roll l^2 which engages a 65 surface of the cam L^3 . The lip or edge l holds the box during the filling operation and is then withdrawn to allow the side tabs $2, 2$, and cover or flap 3 of the carton to be closed in. To close in the tabs $2, 2$, 70 there is shown a shearlike pushing mechanism comprising two levers P, P bent inward and upward at their outer ends as at p so that as they are brought together each 75 will engage one of the tabs and push it down in place. To give it this motion, these levers are mounted on a stud P^1 bolted to a platform A^4 , their other ends being connected by connecting rods P^2 to a common cam lever P^3 attached to a rocking post P^4 mounted in a support P^5 . At the other end of this lever is a cam roll P^6 which engages a cam surface P^7 on the disk C^4 . A spring P^8 attached at one end to the cam lever P^3 and at the other end to the 85 sleeve E^4 holds the cam roll against the cam.

The tabs having been turned in, the flap 3 is next closed upon the carton. For this purpose there is provided a plate Q having 90 a lip q , the plate being sufficiently wide to reach from its bearings Q^1 over the carton and to the farther side thereof. This plate Q is preferably adjustably mounted upon its bearing as shown in Fig. 4 so that it 95 may be adjusted for cartons of different capacities, and it is operated by means of a cam lever Q^2 pivoted to the upright K^2 and having a cam roll q^1 which engages with a cam surface q^2 on the shaft B . A 100 spring q^3 holds the cam roll in proper position in relation to the cam. When rocked the lip q carries the extremity of the flap down into the carton between the farther wall of the carton and the goods. It is then 105 lifted into position to close the next carton when it is filled.

When the carton has been filled and closed the feeding q^1 the next carton pushes the filled carton out through the opening R 110 in the table.

It is believed that the operation of this machine will be understood from the description given above. So far as I know it is the first machine in which a predetermined number of rings have been selected and packed and hence I do not mean to limit myself in any way to the precise details of construction of the machine, my invention comprising selecting mechanism, receiving mechanism by which the rings are received from the selecting mechanism and are deposited in the box or carton and the carton is then closed. Moreover, while it is especially adapted for use with a carton of the kind described, the selecting and depositing mechanism may be used with cartons of other kinds.

While my machine is described as selecting and packaging a predetermined number of jar rings, I do not mean to limit myself to the packaging of such articles alone or to the packaging of a plurality of such articles as the mechanisms described will lend themselves with slight alteration to use in the packaging of articles other than jar rings and to the packaging of a single article as well as a plurality of articles.

What I claim as my invention is:—

1. In a machine of the kind described, a magazine, an arm, means for causing it to engage a predetermined number of articles in said magazine, means for lifting said arm whereby said articles will be separated from others in said magazine, and means for moving said arm away from said magazine whereby said articles will be carried to a place of deposit.

2. In a machine of the kind described, a magazine, means for engaging a predetermined number of articles in said magazine, means whereby said engaging means will be moved to separate said predetermined number of articles from others in said magazine and carry them to a place of deposit, and means for controlling the articles left in the magazine.

3. In a machine of the kind described, a magazine, an arm, means for causing it to engage a predetermined number of articles in said magazine, means for lifting said arm whereby said articles will be separated from others in said magazine, means for moving said arm away from said magazine whereby said articles will be carried to a place of deposit, and means to remove said articles from said arm.

4. In a machine of the kind described, a magazine, an arm, means for causing it to engage a predetermined number of articles in said magazine, means for lifting said arm whereby said articles will be separated from others in said magazine, means for moving said arm away from said magazine whereby said articles will be carried to a place of deposit, and means to remove said articles from said arm and deposit said articles at a predetermined point.

5. In a machine of the kind described, a magazine, an arm, means for causing it to engage a predetermined number of articles in said magazine, means for holding said articles on said arm, means for moving said arm whereby said articles will be conveyed to a place of deposit, and means for releasing said articles from said arm.

6. In a machine of the kind described, a magazine, a head, an arm mounted to be reciprocated therein, means for causing it so to reciprocate, means adapted to cooperate with said arm to hold articles thereon,

means for turning said head whereby said articles may be carried from said magazine, and means for releasing said articles.

7. In a machine of the kind described, a magazine, a head, an arm mounted to be reciprocated therein, means for causing it so to reciprocate, means adapted to cooperate with said arm to hold articles thereon, means for lifting said head and turning it to lift and convey said articles from said magazine, and means for releasing said articles.

8. In a machine of the kind described, a magazine, means to select and withdraw a predetermined number of articles therefrom, means adapted to lift said withdrawing means, and means adapted to move said withdrawing means laterally whereby said articles may be conveyed to a place of deposit.

9. In a machine of the kind described, a magazine, means to select and withdraw a predetermined number of articles therefrom, means to feed articles in said magazine to said withdrawing means, means adapted to lift said withdrawing means, and means adapted to move said withdrawing means laterally whereby said articles may be conveyed to a place of deposit.

10. In a machine of the kind described, a magazine, means to select and withdraw a predetermined number of articles therefrom, means adapted to lift said withdrawing means, means adapted to move said withdrawing means laterally whereby said articles may be conveyed to a place of deposit, and means to remove said articles from said withdrawing means.

11. In a machine of the kind described, a magazine, means to select and withdraw a predetermined number of articles therefrom, means adapted to lift said withdrawing means, means adapted to move said withdrawing means laterally whereby said articles may be conveyed to a place of deposit, and means to remove said articles from said withdrawing means and deposit said articles at a predetermined point.

12. In a machine of the kind described, a magazine, means to select and withdraw a predetermined number of articles therefrom, means adapted to lift said withdrawing means, means adapted to move said withdrawing means laterally whereby said articles may be conveyed to a place of deposit, means to remove said articles from said withdrawing means, a carton feed, and means for causing said removing means to deposit said articles in a carton.

13. In a machine of the kind described, a magazine, means to select and withdraw a predetermined number of articles therefrom, means adapted to lift said withdrawing means, means adapted to move said

- withdrawing means laterally whereby said articles may be conveyed to a place of deposit, means to remove said articles from said withdrawing means, a carton feed, 5 means for causing said removing means to deposit said articles in a carton, and means for closing said carton.
14. In a machine of the kind described, a magazine, means to select and withdraw a predetermined number of articles therefrom, means adapted to lift said withdrawing means, means adapted to move said withdrawing means laterally whereby said articles may be conveyed to a place of deposit, 10 means to remove said articles from said withdrawing means, a carton feed, means for causing said removing means to deposit said articles in a carton, means for closing said carton, and means for removing said 15 carton.
15. In a machine of the kind described, a magazine, means to select and withdraw a predetermined number of articles therefrom, means adapted to lift said withdrawing means, means adapted to move said withdrawing means laterally, means to remove said articles from said withdrawing means, a carton feed, means for engaging one edge of a carton to hold it open, and means for 20 causing said removing means to deposit said articles in said carton.
16. In a machine of the kind described, a horizontal ring magazine, a stop at one end thereof, an intermittent feed adapted to feed 25 rings horizontally toward said stop, means for lifting a predetermined number of rings from said magazine, means for preventing the rings adjacent to said lifted rings from being lifted from said magazine, and means 30 for temporarily retaining said last-named rings from being fed forward while said lifting operation is taking place, said means comprising a slide mounted on the floor of said magazine and adapted to move into said 35 magazine as the selected rings are withdrawn therefrom and engage the front one of the rings left in said magazine.
17. In a machine of the kind described, a magazine adapted to receive and feed rings, 40 and means to select a predetermined number of rings therefrom and convey them to a place of deposit comprising a lifter and means for moving it into the opening in said rings, and a holder adapted to hold rings on 45 said lifter, means for raising said lifter and holder to lift said rings from said magazine, and means for causing said lifter to deposit said rings.
18. In a machine of the kind described, a 50 magazine and means for selecting and lifting rings therefrom comprising a head, means for lifting and turning said head, an arm mounted to slide in said head toward and from said magazine, and means for 55 causing it to slide, and a second arm pivot- 65 ally mounted on said head and adapted to slide thereon and means for causing it to slide.
19. In a machine of the kind described, a magazine and means for selecting and lift- 70 ing rings therefrom comprising a head, means for lifting said head and means for turning said head, an arm mounted to slide in said head toward and from said magazine, and means for causing it to slide, and a sec- 75 ond arm pivotally mounted and adapted to slide thereon and means for causing it to slide, and means for locking said first-named arm when in lifting position to secure said rings thereon and for unlocking said arm 80 to release the rings.
20. In a machine of the kind described, a head, means mounted thereon to have a horizontal movement with relation thereto adapted to select and engage a predeter- 85 mined number of articles, means adapted to lift said head whereby said articles will be lifted, means adapted to turn said head whereby said articles will be carried from one place to another, means located to receive said articles after they have been so carried, said head turning means being adapted thereafter to release said head to its original position whereby said article-selecting, engaging and lifting means may act on 90 a new set of articles.
21. In a machine of the kind described, in combination, a depositing means comprising hands, a common support for said hands, one of said hands being stationary with relation 100 to the other, means for moving the movable hand toward and from the stationary hand along said common support, and means for lifting and lowering said hands.
22. In a machine of the kind described, in combination, a depositing means comprising hands, one of said hands being stationary, with relation to the other, means for moving the movable hand toward the stationary hand, means for adjusting said hands with 110 relation to each other to allow for the thickness of the material to be grasped, and means for moving the hands together from a grasping position to a depositing position.
23. In a machine of the kind described, means for selecting a predetermined number of articles and carrying them to a predetermined point, means for clamping said articles during said carrying operation, 115 hands adapted to receive said articles at said predetermined point and grasp them, means for releasing said articles from said carrying means, means for moving said hands together and causing them to deposit said articles.
24. In a machine of the kind described, means for selecting a predetermined number of articles, means for clamping them 120

- upon said selecting means, and means for carrying them to a predetermined point, hands adapted to receive and hold said articles at said predetermined point, means to 5 operate said clamping means whereby said articles will be released therefrom, and means whereby said hands will convey said articles to a place of deposit, and means to separate said hands at said place of deposit 10 whereby said articles will be left thereat, and means to return said hands to said predetermined point.
25. In a machine of the kind described, in combination, a guideway on which a carton may be moved, means for moving a carton along said guideway, a plate located in a plane crossing the guideway and adapted to engage one of the flaps of the carton as said carton is moved along the guideway, 15 means for moving said carton from said guideway in a direction parallel with said plate, means for depositing one or more articles in said carton, and means for closing said carton.
- 20 26. In a machine of the kind described, in combination, a guideway, means for moving a carton along said guideway to a predetermined position, means comprising a stationary plate located in a plane crossing 25 the guideway and adapted to engage one of the flaps of the carton as it advances along the guideway, means for moving said carton from said guideway in a direction at right angles thereto to a filling position, means 30 for filling said carton, said plate serving to hold said flap in upright position during said filling operation, and means for closing said carton.
27. In a machine of the kind described, in 35 combination, a guideway, means for moving a carton along said guideway, means located at the end of said guideway adapted to move such carton in a direction at right angles to said guideway to a filling position, a plate 40 located across the end of said guideway to engage the flap of said carton and hold it open while said carton is being moved into filling position and during the filling operation, and means for filling the carton.
- 45 28. In a machine of the kind described, in combination, a guideway, means for moving a carton along said guideway, means located at the end of said guideway adapted to move such carton in a direction at right angles to said guideway to a filling position, a plate 50 located across the end of said guideway to engage the flap of said carton and hold it open while said carton is being moved into filling position and during the filling operation, means adapted to hold open the edge of said carton opposite said flap during said filling operation, and means for filling the carton.
- 55 29. In a machine of the kind described, in combination, a guideway, means for moving a carton along said guideway, means located at the end of said guideway adapted to move such carton in a direction at right angles to said guideway to a filling position, a plate 60 located across the end of said guideway to engage the flap of said carton and hold it open while said carton is being moved into filling position and during the filling operation, means for closing said carton, and means for filling the carton while 65 said carton is open.
30. In a machine of the kind described, a guideway, means for feeding a carton along said guideway, a stationary plate extending across said guideway to engage the flap of such carton, said plate having a downwardly-projecting part at the end, which first engages the carton, said plate being substantially narrower at the other end thereof whereby said flap may be pulled 80 out from behind said plate during the folding operation, and means for folding said flap.
31. In a machine of the kind described, a carton feeding means comprising a guideway, oppositely-located clamps, means for moving said clamps toward each other to engage a carton, and means to move said clamps lengthwise of the guideway to feed said carton, and means for depositing articles in said carton, means for feeding said carton from said guideway into position to receive such articles and means for holding the carton open to receive said articles. 90
32. In a machine of the kind described, means for feeding a carton to its filling position, means for filling the carton, and means operable thereafter for closing opposing parts of the carton comprising two levers pivoted together, and means connected 100 to the outer ends thereof whereby the closing ends thereof will be caused to approach each other and engage the said opposing parts of the carton and cause them to be folded toward each other, in combination 105 with means for tucking the flap of said carton thereinto operable after said opposing parts have been folded.
33. In a machine of the kind described, in combination, a magazine, means for selecting a predetermined number of articles therefrom and carrying them to a predetermined point, hands for receiving and grasping said articles at said predetermined point, means for feeding a carton to a filling position, means operable with said hands to deposit said articles in said carton, and means for closing said carton, all of said mechanisms being successively operable in a 115 manner relative to each other.
34. In a machine of the kind described, in combination, a magazine, means for selecting a predetermined number of articles 120

therefrom and carrying them to a predetermined point, means for clamping said articles during such carrying operation, hands adapted to receive and grasp said articles at said point, means for releasing said articles from said carrying means, means for feeding a carton to its filling position, means in operation with said hands to de-

posit said articles in said carton, and means for closing said carton, all of said mechanisms being operable successively and in a manner relative to each other. 10
